DOUGLAS HAYNES CORBIN AND ARTHUR WILLIAM HARRIS, OF BIRMINGHAM
ENGLAND, ASSIGNEES TO LIFE TARGETS LIMITED, OF LONDON, ENGLAND.

CINEMATOGRAPH TARGET APPARATUS.

1,125,662.

Specification of Letters Patent. Patented Jan. 19, 1915.

Application filed May 16, 1914. Serial No. 839,005.

To all whom it may concern:

Be it known that we, DOUGLAS HAYNES CORBIN and ARTHUR WILLIAM HARRIS, subjects of the King of Great Britain, residing 5 at 98 King's Road, Erdington, Birmingham, in the county of Warwick, England, and Durley Dene, Jaffray Road, Erdington, Birmingham aforesaid, respectively, have invented a new and useful Improvement in 10 Cinematograph Target Apparatus; and we do hereby declare the following to be a full, clear, and exact description of the same.

Our invention comprises improvements in 15 cinematograph target apparatus of the kind which is described in the prior Patent No. 1,027,371.

In the specification No. 1,075,894 mechanism is shown whereby when a shot is fired a magnetic clutch in the driving train of the 20 cinematograph normally energized is automatically deenergized while simultaneously therewith a braking device is applied to said driving mechanism whereby motion of the cinematograph is automatically arrested. Said motion arresting device in the prior 25 specification is applied to the driving or beater-shaft of the cinematograph which control the movement of the film, but according to the present invention we provide 30 means whereby in addition to the application of the brake to the driving or beater-shaft a braking or motion arresting device is operated to arrest the motion of the spool boxes, *i. e.* the reels from and onto which 35 the film is wound.

Referring to the drawings:—Figure 1 is a diagrammatic view illustrating one form of the invention with the electrical connections for same. Figs. 2 and 3 are modified 40 forms of braking devices.

In carrying this invention into practice as illustrated upon the accompanying drawings, the shaft 1 is shown as being driven by the motor 2 by a belt 3 and magnetic clutch 4, this shaft 1 serving to control the movement of the film. As illustrated in the accompanying drawings the magnetic clutch 4 corresponds with the magnetic clutch 12—13 in the prior specification No. 1,075,894, and when a shot is fired this clutch 45 is automatically deenergized in a similar manner to that described in the said prior specification.

The shaft 1 is provided with a drum 5 55 surrounded by a band brake 6, one end of

which is anchored while the other end is connected to armature 7 of the magnet 8. This magnet 8 corresponds with the magnet 3 described in the prior specification No. 1,075,894, and when energized will obviously attract the armature 7 applying the brake to the drum 5 the energizing of the magnet taking place in a similar manner to that of the magnet 3 described in the said prior specification.

As in the prior specification the mechanism is so arranged that the cinematograph cannot be stopped when the film is moving for which purpose the shaft 1 carries the drum 9 covered with insulation 10 around 70 the greater part of its periphery and having a contact making portion 11 at one point. A switch arm 12 is provided in circuit with the magnet and when the switch for supplying the magnetic circuit is closed in manner described in the prior specification and the contact arm 12 engages with the part 11 as the said part 11 rotates, the circuit will be finally completed, the armature being attracted; and in order to retain the armature in its attracted condition the armature is provided with a spring contact 13 engaging a contact 14 which makes a shunt circuit 75 through the armature retaining the brake in its applied condition.

In circuit with or in parallel with, the magnet 8 are solenoids 15 which control the braking devices which are applied to the spool boxes marked 16. These braking devices are carried by the cores of the solenoids 15 in such manner that when the solenoids are energized the braking devices are simultaneously applied to both spool boxes thus preventing movement of same owing to their own momentum after the driving mechanism 95 at the cinematograph has been stopped.

At Fig. 2 a modified form of the braking device is shown in which the magnet 20 controls a pivoted armature 21 having a braking extremity 22 adapted to engage with the 100 spool boxes 16.

At Fig. 3 a further form of braking device is shown embodying an electromagnetic winding 22 on the spool shaft this winding 22 being connected to a non-rotatable disk 23. When this winding is energized in similar manner to the solenoids illustrated, it magnetically attracts the disk 24 connected to a spool shaft 25 the motion of which is thus automatically arrested.

What we claim then is:—

1. In cinematograph target apparatus, the combination of a cinematograph; means for arresting the motion of the cinematograph when a shot is fired; a pair of spool boxes; and means for applying a braking action to said spool boxes when the cinematograph is stopped; for the purpose set forth.
  - 10 2. In cinematograph target apparatus, the combination of a cinematograph; means for arresting the motion of the cinematograph when a shot is fired; a pair of spool boxes; and a pair of electromagnetic braking devices one applied to each spool box so arranged that when the cinematograph is stopped the spool brakes are applied; for the purpose set forth.
  - 20 3. In cinematograph target apparatus, the combination of a cinematograph having a driving shaft; an electromagnet; means for energizing said electromagnet when a shot is fired; an armature attracted when the magnet is energized; a pair of spool boxes; and a pair of electromagnetic braking devices one applied to each spool box so arranged that when the cinematograph is stopped the spool brakes are applied; for the purpose set forth.
  - 30 4. In cinematograph target apparatus, the combination of a cinematograph having a driving shaft; an electromagnet; means for energizing said electromagnet when a shot is fired; an armature attracted when the magnet is energized; a spring contact device in circuit with the magnet; an insulated drum adapted to make electrical contact with said spring contact device at one point so as to insure that the cinematograph
  - 35 will be stopped only when the film is not running; a pair of spool boxes; and a pair of electromagnetic braking devices one applied to each spool box so arranged that when the cinematograph is stopped the spool brakes are applied; for the purpose set forth.
  - 40 5. In cinematograph target apparatus, the combination of a cinematograph having a driving shaft; an electromagnet; means for energizing said electromagnet when a shot is fired; an armature attracted when
  - 45
- the magnet is energized; a spring contact device in circuit with the magnet; an insulated drum adapted to make electrical contact with said spring contact device at one point so as to insure that the cinematograph will be stopped only when the film is not running; a band brake connected to and actuated by the armature; a contact device carried by the armature for making a shunt circuit to maintain the braking pressure; a pair of spool boxes; and a pair of electromagnetic braking devices one applied to each spool box so arranged that when the cinematograph is stopped the spool brakes are applied; for the purpose set forth.
6. In cinematograph target apparatus, the combination of a cinematograph having a driving shaft; a brake drum carried by said shaft; an electric motor for driving said cinematograph; an electromagnetic clutch intermediate between the shaft and the driving motor; an electromagnet; means for energizing said electromagnet when a shot is fired; an armature attracted when the magnet is energized; a spring contact device in circuit with the magnet; an insulated drum adapted to make electrical contact with said spring contact device at one point so as to insure that the cinematograph will be stopped only when the film is not running; a band brake connected to and actuated by the armature; a contact device carried by the armature for making a short circuit to maintain the braking pressure; a pair of spool boxes; and a pair of electromagnetic braking devices one applied to each spool box so arranged that when the cinematograph is stopped the spool brakes are applied; for the purpose set forth.
- In testimony whereof, we have signed our names to this specification in the presence of two subscribing witnesses.
